UNITED STATES PATENT OFFICE.

JOHN HOWARD McELROY, OF CHICAGO, ILLINOIS.

PRACTICE GOLF-BALL.

1,262,532.

Specification of Letters Patent. Patented Apr. 9, 1918.

Application filed March 8, 1915. Serial No. 12,741.

To all whom it may concern:

Be it known that I, JOHN HOWARD McELROY, a citizen of the United States, and a resident of Chicago, in the county of Cook and State of Illinois, have invented certain new and useful Improvements in Practice Golf-Balls, of which the following is a full, clear, and exact specification.

My invention consists of a ball for golf practice, composed of a soft, spongy material, so that, while it is of the same size as the regulation golf balls, it is so light that, if used for outdoor practice, it does not fly far enough to make its recovery difficult, no matter how hard or accurate the shot; or, if used in the house, it can be driven against the side of a room without the possibility of damaging the wall or furniture, no matter how hard it is hit. It is also useful for practice at the indoor golf schools, where the balls are driven against a net, necessarily placed rather close to the tee, and is more useful for this purpose than the regulation golf balls, in that its flight is so much shorter than that of the ordinary ball that if the shot is faulty and the ball is sliced or pulled, the lateral curve will be apparent before it strikes the net, whereas a sliced or pulled shot against the nets with an ordinary ball is not readily apparent, as the lateral curve would not tend to show until the ball had traveled in the air a much greater distance than that to the net. Likewise, it makes outdoor instruction in golf easier, as if these light practice balls are used, they will, in the short distance they travel, show up the faults of the strokes, but will be driven such a short distance that it is much easier for the caddy to retrieve them, and so much time does not have to be wasted waiting for their return. In addition to their superiority for practice shots, they have the value of being vastly cheaper to manufacture, so that a golfer can have a large number of them without investing a very considerable sum.

To illustrate my invention, I annex here-to a sheet of drawings, in which,—

Figure 1 is a side elevation of a ball constructed in accordance with my invention; and

Fig. 2 is a vertical section through the same.

As will be seen, the body of the ball is composed of a soft, spongy material, and for this purpose I preferably employ what is known as rubber sponge, which is formed by curing raw rubber, or a raw rubber compound, impregnated with a gas-generating chemical, so that when it is cured the chemical causes the rubber to become expanded into a cellular structure, much like salt-rising bread, only with somewhat coarser cells. I preferably use just enough raw material for each ball so that it is of the proper size when cured, so that the skin, corresponding to the crust of a loaf of bread, may be left in place, thus adding materially to its durability, as if the skin were trimmed off, as must be done in manufacturing rubber sponges, it would of course not be so durable, although the trimmed ball is superior in that it flies a slightly less distance under the same impact.

What I claim as new, and desire to secure by Letters Patent of the United States, is:

As a new and useful article of manufacture, a spherical integral practice golf ball composed throughout its body of light rubber made up of large air cells having thin walls, and having a thin, imperforate skin or cover of the same material, but lacking the air cells, formed integral therewith.

In witness whereof, I have hereunto set my hand and affixed my seal, this sixth day of March, A. D. 1915.

JOHN HOWARD McELROY. [L. S.]
